UNITED STATES PATENT OFFICE.

SAMUEL J. KIMBALL, OF ELGIN, ILLINOIS, ASSIGNOR, BY MESNE ASSIGNMENTS, TO VAN SICKLEN CORPORATION, A CORPORATION OF DELAWARE.

CONTAINER.

Application filed February 3, 1928. Serial No. 251,530.

This invention relates to improvements in containers and has for an object to provide a container particularly adapted for attachment to an automobile or the like to contain vanity cases, smokers' articles, etc., and which may be formed entirely of sheet metal or the like, and economically and conveniently assembled to present an ornamental appearance and provide a strong and enduring device. 5 Other objects will be apparent from the disclosure of the following specification and shown in the accompanying drawings, in which—

Fig. 1 is a plan view of a container embodying my invention;

Fig. 2 is a vertical section along the line 2—2 of Fig. 1;

Fig. 3 is a horizontal section along the line 3—3 of Fig. 2;

20 Fig. 4 is a vertical section along the line 4—4 of Fig. 1;

Fig. 5 is a perspective view in elevation of the entrance plate;

Fig. 6 is a perspective of the back plate 25 and false back plate in disassembled relation;

Fig. 7 is a perspective of the front plate in elevation.

Like numerals refer to like elements 30 throughout the drawings in which 10 designates a back plate having a base portion 11 formed integral therewith and angularly disposed as illustrated in Fig. 6. The back plate is provided with an attachment lug 12 struck out of the base portion 11 and extended substantially in the direction of the back plate proper, such construction providing a hole 11^c for discharge of dirt, ashes, water or the like. A screw hole 12^a or the like is 35 provided in this lug. An attachment slot of the inverted key-hole type is indicated by numeral 13, and is constructed with the enlarged and reduced portions of well known form to permit insertion of a screw head or the like in the enlarged portion, and the later dropping of the back plate to prevent withdrawal of the container from the supporting screw.

The back plate is provided with the angularly formed side flanges 10^a and the base portion 11 is provided with the vertically disposed flange 11^a at its outer edge.

50 A front plate, generally indicated by numeral 15, is provided, the same being shaped to conform to the contour of the base portion

11 and having the side wings 15^a, 15^b. Vertically arranged supporting strips 16 of pasteboard or the like are glued or otherwise attached to the inner face of the front plate 15, as shown in Fig. 7, for example.

60 A false back plate 20 is also provided, the same being shown in partially disassembled relation in Fig. 6. This plate is provided with the rearwardly and upwardly inclined upper flange 20^a curved to conform to the contour of the upper edge of the back plate 10 and is provided with the off-set bottom flange 20^b constructed to contact with the inner face of the back plate 10, as shown in Figure 4, for example. A pair of supporting lugs 20^d 65 are struck out from the front of the false back plate 20, for a purpose hereinafter described. In the assembly of the elements thus described, the false back plate is secured by spot welding or the like, as at the points 20^c 70 indicated in dotted lines (see Fig. 6), to the inner face of the back plate 10. The outer edge of the upper flange 20^a is shaped to contact and closely fit the upper edge of the back plate 10, as shown in Fig. 4.

75 The front plate 15 is attached by spot welding at the points 15^c, for example, near the outer edge of each wing 15^a, 15^b, to the back plate side flanges 10^a and by spot welding at 80 the point 15^d for example to the base portion 85 flange 11^a. The device as thus far assembled may then be covered by any suitable finishing material such as leather or the like, as indicated by numeral 30 (see Fig. 4 for example).

85 An entrance plate is desirable in many instances, and I have illustrated the form of such plate in Fig. 5, generally designated by numeral 35, this comprising a plate of such contour as to closely fit the opening between the front plate 15 and the false back plate 90 95 20. An entrance aperture 35^a is provided and flanges 35^c, 35^d, are integrally formed therewith and project downwardly therefrom at the rear and front of the aperture 35^a respectively, while similar flanges 35^e are integrally formed and project downwardly at the ends of the aperture 35^a (see Figs. 4 and 5). The flange 35^c is provided with the rearwardly directed portion 35^f angularly disposed with respect thereto and lying adjacent 100 or contacting the false back plate 20. Near either end, at the rear edge of the entrance plate 35 are the depending integral legs 35^g.

105 This entrance plate is also susceptible of covering with an ornamental or protective 110

coating on the upper exposed surface, which covering may be carried around the edges of the entrance plate to the unexposed surfaces and secured thereto, thereby covering the edges to obviate the liability of the leather becoming detached or fraying. After such covering the entrance plate is inserted in the opening between the front plate 15 and the false back plate 20 as illustrated in Fig. 5, for example, the supporting strips 16 serving to position and support this entrance plate. Lugs 20^d are also arranged to support the legs 35^g and thereby assist in the support and positioning of the entrance plate. The entrance plate may be glued or otherwise secured in assembled relation to the container and provides not only a means of access to the interior of the container but serves to position such articles of utility or the like as may be carried or placed in the container, as for example, an ash tray, mirror, vanity case or the like.

The container thus constructed may be made highly ornamental in appearance, of relatively light weight, and of comparatively great strength and durability, and is susceptible of economical production in quantities with relatively rapid and accurate assembly. Where the parts are all stamped or formed from sheet metal a number of uncertain delicate operations which have hitherto been considered necessary in the manufacture of devices of this character is dispensed with.

The head of the supporting screw extending through the opening 13 is guarded from contact with any articles carried in the container and substantial body and thickness is simulated by the provision and construction of the false back plate.

It will be obvious that the container illustrated and described above is susceptible of modification and variation and I do not wish to be restricted to the form shown and described except as defined within the scope of the appended claims.

What I claim is:

1. A container comprising a back plate having a base portion integral therewith and angularly disposed, a lug struck out of said base portion, said back plate being further provided with an attachment aperture spaced from said lug, a front plate secured to said back plate and portion, and a false back plate spaced from said back plate and overlying said aperture.

2. A container comprising a back plate having a base portion integral therewith and angularly disposed, means for attachment of said back plate to a support, a front plate secured to said back plate and base portion, and a false back plate spaced from said back plate, said false back plate being flanged at its upper edge to contact with said back plate and being secured thereto.

3. A container comprising a back plate

having a base portion integral therewith and angularly disposed, means for attachment of said back plate to a support, a front plate secured to said back plate and base portion, and a false back plate spaced from said back plate, said false back plate being flanged at its lower edge to contact said back plate and being secured through said flange to said back plate.

4. A container comprising a back plate having a base portion integral therewith and angularly disposed, means for attachment of said back plate to a support, a front plate secured to said back plate and base portion, and a false back plate spaced from said back plate, said false back plate being flanged at top and bottom to contact with said back plate and being secured thereto.

5. A container comprising a back plate having a base portion integral therewith and angularly disposed, means for attachment of said back plate to a support, a front plate secured to said back plate and base portion, and a false back plate spaced from said back plate, said false back plate being provided with an offset lower flange secured as by spot welding to said back plate.

6. A container comprising a back plate having a base portion integrally formed therewith and angularly disposed with respect thereto, said back plate being provided with said flanges, said base portion being also provided with a flange, and a front plate shaped to conform to said base portion and secured as by spot welding to said side and base portion flanges.

7. A container comprising a back plate having an angularly disposed base portion, a front plate secured to said back plate and base portion, and an entrance plate mounted in the opening between said front and back plates, said entrance plate being provided with an entrance aperture to permit access to the interior of said container.

8. A container comprising a back plate having an angularly disposed base portion, a front plate secured to said back plate and base portion, and an entrance plate mounted in the opening between said front and back plates, said entrance plate being provided with an entrance aperture to permit access to the interior of said container and being also provided with downwardly directed flanges at the sides of said aperture.

9. A container comprising a back plate having an angularly disposed base portion, a front plate secured to said back plate and base portion, a false back plate located inwardly of said back plate and secured thereto, an entrance plate mounted in the opening between said front plate and said false back plate, and means to support said entrance plate in proper assembled relation with respect to said front and false back plates.

10. A container comprising a back plate

- having an angularly disposed base portion, a front plate secured to said back plate and base portion, a false back plate located inwardly of said back plate and secured thereto, an 5 entrance plate mounted in the opening between said front plate and said false back plate, and means to support said entrance plate in proper assembled relation with respect to said front and false back plates, said 10 last named means including lugs carried by said false back plate.
11. A container comprising a back plate having an angularly disposed base portion, a front plate secured to said back plate and 15 base portion, a false back plate located inwardly of said back plate and secured thereto, an entrance plate mounted in the opening between said front plate and said false back plate, and means to support said entrance 20 plate in proper assembled relation with respect to said front and false back plates, said last named means including supporting strips at the inner face of said front plate.
12. A container comprising a back plate 25 having an angularly disposed base portion, a front plate secured to said back plate and base portion, a false back plate located inwardly of said back plate and secured thereto, an entrance plate mounted in the opening 30 between said front plate and said false back plate, means to support said entrance plate in proper assembled relation with respect to
- said front and false back plates, said last named means including supporting strips at the inner face of said front plate, and lugs 35 carried by said false back plate.
13. An article of manufacture comprising a container constructed of separately formed front and back plates secured together and a separately formed apertured entrance plate 40 inserted in the opening between said front and back plates.
14. An article of manufacture comprising a container constructed of separately formed front and back plates secured together and a 45 separately formed apertured entrance plate inserted in the opening between said front and back plates, the aperture in said entrance plate being constructed and arranged to accommodate and position articles placed in 50 said container.
15. A container comprising a back plate provided with an angularly disposed base plate, a front plate attached to the base plate and back plate forming a container, an entrance plate for the container and a false back extending the length of the cover member and upwardly therefrom to lend an appearance of thickness to the back portion 55 above the cover member. 60

In testimony whereof, I have signed my name to this specification.

SAMUEL J. KIMBALL.
